HEDDLE FRAME

Russell P. Drake, Caledonia, Ill., assignor to
Barber-Colman Company, Rockford, Ill., a cor-
poration of Illinois

Continuation of application Serial No. 514,313,
December 15, 1943. This application May 31,
1946, Serial No. 673,240

14 Claims. (Cl. 139—92)

1

This invention pertains to an improved heddle supporting frame, and its general aim is to facilitate the removal and replacement of heddles relative to the frame.

For a more specific object, the invention aims to provide for the mounting of the heddle supporting bars in the frame in such a way as to permit shifting of one or more ends of the bars laterally relative to the frame, thereby exposing the ends of the bars for the removal and replacement of the heddles.

Another object is to provide means operative to hold the bars firmly in their laterally shifted positions so as to free the hands of the operator in threading heddles onto the bars or in removing them from the bars.

The objects of the invention thus generally stated, together with other and ancillary advantages, are attained by the construction and arrangement shown by way of illustration in the accompanying drawings, in which:

Figure 1 is a face view of a heddle frame embodying the features of the invention and showing the preferred construction.

Fig. 2 is an enlarged fragmentary end view of the heddle frame with portions thereof broken away.

Fig. 3 is an enlarged fragmentary face view of the portion shown in Fig. 2.

Fig. 4 is a fragmentary sectional view taken on the line 4—4 of Fig. 3.

Fig. 5 is a face view of a modified form of heddle frame.

Fig. 6 is an enlarged view of a portion of the heddle frame shown in Fig. 5.

Fig. 7 is a fragmentary sectional view taken on the line 7—7 of Fig. 6.

Fig. 8 is a fragmentary sectional view taken on the line 8—8 of Fig. 6.

The heddle frame apart from the heddle supporting means is of conventional construction. Thus, it comprises top and bottom side rails 10 and 11, preferably of wood, and end members 12, each comprising a pair of generally U-shaped straps 13 and 13' having yoke portions welded together and providing parallel end portions 14 spaced apart to receive between them the ends of the rails 10 and 11, such end portions being suitably secured to the rails.

The present invention concerns the mounting within the frame of a pair of heddle supporting bars 15 so as to permit of detachment of the ends of the bars from the frame and the shifting of the bars into a position such as to permit easy removal of the heddles from the frame and the

replacement thereof. In general, each of the supporting bars 15 is releasably secured at its opposite ends upon the end members 12 by means of latch devices 16, and each is supported intermediate its ends from the adjacent rail 10 or 11 of the frame by means of one or more anchoring devices 17.

In the preferred embodiment of the invention, the heddle supporting frame is designed for use with heddles 18 having hooks 19 at opposite ends. Accordingly, the heddle supporting bars 15 are generally channel shaped in cross section, with one leg forming a narrow wall or heddle flange 20 with a free edge portion exposed for engagement by the heddle hooks 19 and the other leg 21 extended to form a relatively wide anchoring member connected to the adjacent side rail 10 or 11 by means of the anchoring devices 17, two such devices being herein employed in the case of each rail.

Referring now to the embodiment of the invention illustrated in Figs. 1 to 4, inclusive, each of the latch devices 16 comprises a leaf spring 22 fastened to the inner side of one of the end members 12. The leaf spring is normally inclined relative to the end member and carries at its free end a detent element 23 in the form of a finger projecting through a notch 24 in the bottom of the channel member, as best shown in Figs. 3 and 4 into the recess or space formed by the channel. The detent element is dimensioned to fit snugly between the legs 20 and 21 of the bar, thereby holding the end of the bar against lateral movement relative to the frame.

When it is desired to release the bar for shifting movement, the detent is shifted manually a short distance inwardly or away from the end member 12 into alignment with a slot 25 merging or opening at one end into the notch 24. Movement of the detent element into such position permits of movement of the supporting bar laterally into a position indicated at *a* in Figs. 2 and 4, at one side of the frame. It will be observed that when the bar is thus shifted the detent is released from the bar so that the spring 22 may be pressed against the frame member 12 to position the detent between said member and the end of the bar which is spaced a short distance from said end member, as shown in Fig. 3.

With the detent held manually in position against the end member, the supporting bar may be shifted reversely to a position designated *b* on the opposite side of the frame. In this position, the free end of the bar is exposed so as to permit loading or removal of the heddles.

An important feature of my invention resides in the utilization of the latch device for holding the heddle supporting bar in such heddle loading position *b*. For this purpose, the leaf spring 22 is provided with a latch element 26, herein in the form of a second finger somewhat longer than the detent element 23. When the bar is shifted into its heddle loading position *b* the leaf spring 22 is released by the operator so as to permit movement of the latch element 26 into position behind the anchoring leg 21 of the bar, this being the normal position of the latch device. It is to be observed that because the latch element 26 engages the outer face of the anchoring leg of the bar the heddles are free to slide along the heddle flange 20 of the bar. Moreover, since the bar is held in this position, while under stress, it is held firmly by the resiliency of the bar so that the operation of removing heddles from the bar or replacing them thereon is greatly facilitated.

In the embodiment of the invention shown in Figs. 5 to 8, latch devices 16' are employed. In this instance, each device comprises a detent member in the nature of a slide bolt 27 mounted for sliding movement transversely of the end members 12 and engageable in an end opening recess formed by the channel of the supporting bar to hold the latter in normal position. For a reason which will presently appear, the supporting bar in this instance occupies a reverse position from that of Figs. 1 to 4, with the heddle flange of the channel bar disposed on the side remote from the observer (Figs. 5 and 6).

Herein, the slide bolt 27 is in the form of a flat plate supported in a slot 28 formed in the two straps 13 and 13' constituting the end member 12 (see Fig. 8). Its outer end is connected with the free end of a leaf spring 29 anchored to the outer side of the end member 12 and acting to hold the slide with its inner end entered between the legs 20 and 21 of the bar. At its inner end, the slide carries a lug 30 disposed above the channel leg 20 and projecting laterally to one side face of the frame. Upon withdrawal of the slide bolt against the action of the spring into a position between the frame member and the end of the bar (this position being shown in broken lines in Fig. 8), the bar is released for lateral shifting movement. After the bar has been shifted into the dotted line position *a'* of Fig. 8, the slide is released to the action of the spring, positioning the lug 30 for engagement with the anchoring leg 21 of the bar and leaving the heddle flange 20 unobstructed for the removal or replacement of the heddles.

The latch device 16' is preferably constructed so as to coact with the frame in the normal position of the device so as to be held by the frame against accidental movement. For this purpose, the upper end of the leaf spring 29 is bent over to project through an opening in the slide bolt 27 and is extended to form a U-shaped member 31 engageable with one edge portion of the end member 12, the spring being biased in a direction to move the bolt inwardly and also to move the U-shaped portion 31 transversely of the frame into engagement with the end member.

The anchoring devices 17 by means of which the heddle supporting bars are supported intermediate their ends are preferably constructed to permit of adjustment to compensate for any bowing of the rails 10 and 11 incident to the application of transverse forces thereto in the use of the frames. For this purpose, each of such an-

choring devices comprises a rod 32 extending through a hole 33 in the rail and having a bent inner end to form a hook 34 for attachment to the supporting bar. The outer end of the rod is threaded for the reception of a nut 35 clamped in position in a recess in the rail, by a plate 36, the latter engaging a collar 37 on the nut. By a rotational adjustment of the nut 35, the position of the rod 32 relative to the rail may be adjusted as may be desirable to compensate for any bowing of the rail.

The hook 34 of the rod 32 is preferably secured to the supporting bar in such a way as to hold the rod in the plane of the bar. For this purpose the upper edge of the bar is formed with a transverse flange 39 having a flat upper surface, and the hook 34 has a flat side which is held in position against said surface by a lug 40 formed integral with the flange 39 and curled or looped around the rod, as shown in Figs. 6 and 7. The lugs 40 are relatively short so that with one end of the heddle supporting bar shifted laterally clear of the end member 12, the bar need be moved longitudinally only a short distance to disengage it from the hooks 34.

In view of the fact that the upper heddle supporting bar has its channel opening upwardly, it is desirable that provision be made for the removal of lint which may be deposited in the channel. For this purpose, a series of slots 41 may be provided along the channel near the bottom thereof, such slots being, in the present instance, formed in the anchoring leg 21 thereof.

It will be seen that through the provision of latch devices 16 or 16', I have provided for the mounting of the heddle supporting bars so as to facilitate placement of the heddles in the frame of their removal therefrom. In each instance, the latch devices are operative not only to hold the bars in their normal or operative relation to the frame but also to hold them firmly against the normal resiliency of the bars, in position to permit of easy handling of the heddles.

In the embodiment shown in Figs. 1 to 4, the latch device is manipulated (to release the bar) first into a position to permit lateral shifting of the bar in one direction, to the position shown at *a* in Fig. 4, the detent element 23 being manually held in alignment with the open ended slot 25 during such movement. Secondly, the spring is compressed against the end member 12 and into position between this member and the end of the bar, whereupon the latter may be swung to the opposite or *b* position. Finally, the latch is released so that the latch element 26 moves into position to engage with the anchoring leg 21 of the bar, leaving the opposite or heddle supporting leg unobstructed for the sliding movement of the heddles.

In the case of the embodiment shown in Figs. 5 to 8, the slide bolt is shifted against the action of the leaf spring 29 from the normal or operative position shown in Fig. 6 to a withdrawn position in which the bolt is removed entirely from between the two legs of the channel shaped bar. In this instance, withdrawal of the slide bolt releases the bar for movement directly into its disengaged or heddle loading and unloading position. Upon movement into such position the slide bolt is released to the action of the spring 29, thereby carrying the lug 30 into position against the anchoring leg 21 of the bar.

The means for supporting the heddle bars in the frame, including the anchoring devices 17, is not herein claimed but forms the subject of a

divisional application, Serial No. 591,008, filed April 30, 1945.

This application is a continuation of my co-pending application Serial No. 514,313, filed December 15, 1943, now abandoned.

I claim as my invention:

1. In a supporting frame for heddles having end hooks, the combination of a side rail and an end member, a heddle supporting bar extending parallel to said rail, said bar being of channel cross section and comprising an anchoring leg connected to said rail and a heddle leg forming a flange having a free edge for engagement by the heddle hooks, and a latch device mounted on the end member and having a detent element normally engaging between the legs of the channel shaped bar to hold the bar against lateral movement relative to the frame and a latch element engageable with the anchoring leg of the bar to hold it in laterally shifted position relative to the frame.
2. In a supporting frame for heddles having end hooks, the combination of a side rail and an end member, a heddle supporting bar extending parallel to said rail, said bar being of channel cross section and comprising an anchoring leg connected to said rail and a heddle leg forming a flange having a free edge for engagement by the heddle hooks, and a latch device mounted on the end member and having a latch element engageable with the anchoring leg of the bar to hold it in laterally shifted position relative to the frame.

3. A frame for supporting heddles having reversely bent end hooks, comprising, in combination, top and bottom rails, end members connecting said rails, a pair of heddle supporting bars connected intermediate their ends with the top and bottom rails respectively, each of said bars being channel shaped in cross section with one leg of the channel forming a supporting flange for engagement by one of said hooks, and a latch device releasably securing one end of each of said bars to an end member, each of said latch devices comprising a leaf spring secured to the end member and having at its free end a detent disposed in the channel formed in part by the flange, said bar having a slot spaced a short distance from its end adapted to receive said detent to permit lateral shifting of the bar, and the bottom of the channel being notched to permit movement of said detent into position at one side of said slot whereby to hold the bar against movement relative to the frame.

4. In a supporting frame for heddles having reversely bent end hooks, the combination of a side rail and an end member, a heddle supporting bar extending parallel to said rail, said bar being of channel shape in cross section and having an anchoring leg connected to said rail at a point spaced from said end member and an opposed leg forming a flange for engagement by the heddle hooks, a leaf spring secured to the end member and having at its free end a detent disposed in said channel to hold the end of the bar against lateral shifting movement relative to the end member, said channel bar having a notch in the bottom of the channel to permit movement of the detent into holding relation to the channel.

5. In a supporting frame for heddles having end hooks, the combination of a side rail and an end member, a heddle supporting bar extending parallel to said rail with one end spaced a short distance from the end member, said bar being of channel shape and comprising an anchoring

leg connected to said rail at a point spaced from said end member, and a heddle supporting leg having a free edge for engagement by the heddle hooks, a leaf spring attached to said end member, a detent element on the free end of said spring engageable in the channel of the bar to hold the latter in normal position, said bar having a notch in the bottom of said channel permitting movement of the detent into and out of holding relation to the bar, and a latch element on the free end of said spring, said detent element being movable into position between the bar and the end member to permit movement of the bar into a laterally shifted position, and said latch element being engageable with the bar in such laterally shifted position to hold it in such position.

6. In a supporting frame for heddles having end hooks, the combination of a side rail and an end member, a heddle supporting bar extending parallel to said rail with one end of the bar spaced a short distance from the end member, said bar being of channel shape and comprising an anchoring leg connected to said rail and a heddle supporting leg having a free edge for engagement by the heddle hooks, a leaf spring attached to said end member, a latch element on the free end of said spring engageable with the supporting leg of the bar at one end thereof to hold the latter out of the plane of the frame, said spring being movable into position between the bar and the end member to permit the bar to move into a normal position relative to the frame, and a detent element also carried by said spring and engageable in the channel in the normal position of the bar to hold it in such position, said bar having an open ended slot spaced from the end of the bar adapted for the reception of the detent element when the latter is moved to a release position in alignment with the slot whereby to permit movement of the bar into normal position relative to the frame and said bar further having a notch at the bottom of said channel to permit movement of the detent element into holding position between the legs of the channel.

7. In a supporting frame for heddles having reversely bent end hooks, the combination of a side rail and an end member, a heddle supporting bar extending parallel to said rail with one end of the bar spaced a short distance from the end member, said bar being of channel shape and comprising an anchoring leg connected to said rail, and a heddle supporting leg having a free edge for engagement by the heddle hooks, a leaf spring attached to said end member, a detent element on the free end of said spring engageable between the legs of the bar to hold the latter in normal position in said frame, said spring being movable into position to carry said detent element clear of the end of the bar whereby to permit movement of the bar into a laterally shifted position relative to the frame, and a latch element on said spring engageable with the anchoring leg of said bar in the shifted position of the latter to hold it in such position.

8. In a frame for supporting heddles having reversely bent end hooks, the combination of a side rail and an end member, a heddle supporting bar extending parallel to said rail and having an elongated edge portion adapted for engagement by the heddle hooks and a supporting portion spaced laterally from said edge portion, means for supporting said bar from said side rail including an anchoring device carried by the

side rail and attached to the supporting portion of the bar at a point spaced from one end of the bar a distance sufficient to permit free lateral swinging movement of such and relative to the end member, and a latch device carried by said end member and adapted to engage the supporting portion of the bar to hold it in a laterally shifted position relative to the frame.

9. In a supporting frame for heddles having reversely bent end hooks, the combination of a side rail and an end member, a heddle supporting bar extending parallel to said rail, said bar being of channel shape in cross section and comprising an anchoring leg connected to said rail at a point spaced from the end of the bar and a heddle flange for engagement by the heddle hooks, a bolt slideable in the end member and into and out of position between the legs of said bar, and a transversely extending latch element on said bolt engageable with said anchoring leg of the bar to hold the latter in deflected position relative to the frame.

10. In a supporting frame for heddles having reversely bent end hooks, the combination of a side rail and an end member, a heddle supporting bar extending parallel to said rail, said bar being of channel shape in cross section and comprising an anchoring leg connected to said rail at a point spaced from the end of the bar and a heddle flange for engagement by the heddle hooks, and a latch device comprising a leaf spring attached to the end member and a bolt on the free end of the spring slidably mounted in the end member and normally held by the spring in position between the legs of the channel bar, said leaf spring being yieldable transversely of the plane of the frame and having a part engageable with the end member operative to hold the latch device in normal position relative to the end member.

11. In a frame for supporting heddles having end hooks, the combination of a side rail and an end member, a heddle supporting bar supported intermediate its ends from and in parallel relation to said rail with one end of the bar terminating short of the end member, and a latch device mounted on the end member and having a disengageable connection with said bar, said device comprising a leaf spring secured at one end to the end member and having its free end a detent element normally interengaging with the heddle supporting bar to hold the latter against lateral deflection, said bar having a slot permitting passage of said detent element only upon movement of the element from its said normal position into registry with the slot as permitted by said spring.

12. In a heddle supporting frame, the combination of a side rail, an end member, a heddle supporting bar supported intermediate its ends from and in parallel relation to said rail with one end of the bar terminating short of the end member, and a latch device yieldably mounted on the end member and having a detent element nor-

mally interengaging with the bar to hold the latter against lateral deflection, said bar having a slot positioned in offset relation to the detent element when the latter is in its normal position and permitting passage of the element when the latter is shifted into registry with the slot whereby to permit disengagement of the bar from said latch device.

13. A heddle supporting frame comprising a side rail, an end member, a heddle supporting bar supported intermediate its ends from and parallel with said rail with one end of the bar terminating short of the end member, and a latch device yieldably mounted on the end member and having a detent element normally positioned adjacent the inner side of said end member, said bar and detent element having coacting parts engageable in the normal position of the detent element to prevent lateral deflection of the bar in said frame, and said bar further having a slot disposed in offset relation to the detent element when the latter is in its normal position and permitting passage of the detent element when the latter is shifted into registry with the slot whereby to permit disengagement of the bar from the latch device laterally of the frame.

14. In a heddle supporting frame having a side rail and an end member, a heddle supporting bar supported intermediate its ends from and in parallel relation to said rail with one end of the bar terminating short of the end member and freely swingable relative thereto, and latch means for disengageably holding said bar either in normal position relative to said end member or in laterally offset relation thereto, said latch means comprising two latch elements one yieldably mounted on the end member and shiftable into a predetermined releasing position and the other forming a part of said bar, said latch elements respectively providing laterally spaced abutments and a detent normally engaging between said abutments to hold the end of the bar against lateral swinging movement in either direction, and one of said latch elements being slotted to permit disengagement therefrom of the other latch element when the element carried by the end member occupies its said releasing position.
